(57) **CLAIM**

The ornamental design for a puzzle board, as shown and described.

DESCRIPTION

FIG. 1 is a perspective view of a puzzle board according to a first embodiment showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 in FIG. 1.

FIG. 11 is a perspective view thereof, showing the puzzle board in a folded configuration.

FIG. 12 is a perspective view of a puzzle board according to a second embodiment showing my new design;

FIG. 13 is another perspective view thereof;

FIG. 14 is another perspective view thereof;

FIG. 15 is a front elevational view thereof;

FIG. 16 is a rear elevational view thereof;

FIG. 17 is a left side elevational view thereof;

FIG. 18 is a right side elevational view thereof;

FIG. 19 is a top plan view thereof;

FIG. 20 is a bottom plan view thereof; and,

FIG. 21 is a perspective view thereof, showing the puzzle board in a folded configuration.

The dash-dash broken lines show portions of the puzzle board and form no part of the claimed design. The dash-dot

(Continued)

broken lines in FIGS. 1 and 10 show the bounds of the detail view and form no part of the claimed design.

1 Claim, 21 Drawing Sheets
